UNITED STATES PATENT OFFICE.

FRED L. ELLIOTT AND GEORGE E. ECKERSTROM, OF CHICAGO, ILLINOIS.

PRINTER'S LEAD AND RULE CUTTER.

1,000,789.

Specification of Letters Patent. Patented Aug. 15, 1911.

Application filed September 29, 1910. Serial No. 584,549.

To all whom it may concern:

Be it known that we, FRED L. ELLIOTT and GEORGE E. ECKERSTROM, citizens of the United States, residing at Chicago, in the county of Cook and State of Illinois, have invented certain new and useful Improvements in Printers' Lead and Rule Cutters; and we do declare the following to be a full, clear, and exact description of the invention, such as will enable others skilled in the art to which it appertains to make and use the same.

This invention relates to improvements in printers' lead and rule cutters.

15 One object of the invention is to provide a machine of this character having an improved construction of adjustable gage, adapted to be set for gaging leads, rules, slugs and the like of any desired length.

20 Another object is to provide a lead and rule cutter having means whereby thin material will be securely held and prevented from curling up while being cut.

With the foregoing and other objects in view, the invention consists of certain novel features of construction combination and arrangement of parts as will be more fully described and particularly pointed out in the appended claims.

30 In the accompanying drawings: Figure 1 is a side view of a rule and lead cutting machine constructed in accordance with the invention; Fig. 2 is a top plan view of the same; Fig. 3 is an end view thereof; Fig. 4 is a vertical longitudinal section on the line 4-4 of Fig. 2; Fig. 5 is a vertical section on the line 5-5 of Fig. 2; Fig. 6 is an enlarged vertical sectional view of the adjustable stop for holding the material at the desired position for being cut; Fig. 7 is a detail perspective view of the plate for making "point" adjustments.

In the embodiment of the invention we provide a supporting frame 1 having at its opposite ends suitable supporting legs 2 whereby the same may be secured to a bench or other support. On one end of the frame is secured a stationary material supporting table 3 while on the opposite end of the frame is mounted a spring cutting table 4, said table being pivotally or hingedly connected at its outer end to the adjacent end of the table and is provided on its opposite side edges adjacent to its inner end with laterally projecting supporting lugs 5 which are slidably engaged with slots formed in

the inner sides of spring sockets 6 arranged on opposite sides of the frame 1 as shown. In the sockets 6 are arranged coiled springs 7 with the upper ends of which are engaged 60 the lugs 5 whereby the inner end of the table is yieldingly supported and held in position to receive the material from the stationary table 3. In the upper ends of the sockets 6 are arranged screw plugs 8 which prevent 65 the lugs from being disengaged from the upper ends of the socket.

On the lower portion of the frame 1 is arranged a longitudinally disposed rack bar 9 the notches in which represent half pica 70 lengths. Slidably engaged with the rack bar 9 is an adjustable stop block 10 the upper end of which projects through a longitudinally disposed slot 11 formed in the table 4 and extending throughout the length of 75 the same. The stop block 10 is provided with a toothed pawl 12 which is held in operative engagement with the rack bar 9 by a suitable spring 13. Pivottally connected to the opposite sides of the block 10 below the table 4 80 is the bifurcated lower end of a pawl releasing lever 15, the upper or handle end of which projects through the slot 11 and is provided with a thumb piece whereby said lever may be depressed thereby rocking the 85 pawl 12 and disengaging the teeth thereof from the teeth of the rack bar. When the pawl is thus disengaged from the rack bar the stop block may be adjusted longitudinally in the frame to provide a stop which 90 will enable the material to be cut off at any desired length.

The upper portion 16 of the stop block or the portion engaged by the material to be cut is separate from the lower portion of 95 the block and is adjustably secured to said lower portion by a set screw 17, which is engaged with a slot in said upper portion 16 of the block. By thus connecting the upper portion 16 of the block to the lower portion, 100 said upper portion may be adjusted longitudinally to provide for the more accurate cutting of the rules or leads in the desired lengths.

In order that the material may be cut 105 into lengths known as "points" we provide an adjustable point marking plate 18, said plate being preferably constructed in the form of a cross or provided with radially projecting lugs a, b, c and d. The plate 18 110 is revolvably mounted in a slot 19 formed in the forward upper portion of the stop block

and is adapted to be turned in said slot to bring different lugs into operative position with respect to the end of the block, so that said ends may be lengthened or shortened thus enabling point length adjustments to be made by the block 10. As is well known in the printing art, twelve points represent one pica, so that, for instance, if it should be desired to cut a rule of ten 10 points length or spaces, the stop block would be set to the one pica position on the rack bar and table after which the plate 18 would be adjusted in the block to bring the lug *c* into operative position wherein the same 15 projects beyond the end of the stop block to the distance of two points thereby forming a space of ten points in length with which the rule or lead is engaged for being cut to this length. In the same manner if an eight 20 point lead or rule was desired the plate would be revolved to bring the lug *b* into operative position, in which position said lug will project four points beyond the end of the stop block thereby forming a space of 25 eight points in length between the cutting blade and the end of the lug *b*. When it is not desired to use the plate 18 the latter is turned to bring the lug marked *d* into position, said lug being of such length that the 30 outer edge thereof is flush with the outer edge of the stop thereby making said plate ineffective. The plate 18 is fastened in its adjusted position by a set screw 20 which has a screw threaded engagement with a 35 bracket secured to one side of a stop block as shown. The set screw is provided with a reduced inner end which is adapted to be screwed into engagement with apertures 21 one of which is formed in each of the lugs of 40 the plate 18 as shown.

The table 4 is provided on its upper side adjacent one edge of the slot 11 formed therein with a pica scale of measurement reading from one pica to forty-two picas. 45 The rack bar 9 corresponds in length to the length of said pica scale and the stop block 10 is adapted to be adjusted on said rack bar to the distance of forty-two picas. Should it be desired to cut leads or rules of greater 50 length than forty-two picas, the length of said rules or leads will be measured by a supplemental gage bar 22 which is slidably mounted in a suitable guide bracket 23 arranged on the lower side of the frame adjacent to its outer end as shown. The gage bar 22 is provided on its outer end with an upwardly and inwardly projecting stop arm 24 the inner end of which is provided with a head 25 having a square inner face adapted 55 to receive the end of the rule or lead to be cut. In one side of the gage bar 22 is formed a series of notches which are spaced apart at full pica lengths. The bar 22 is rigidly secured in its adjusted position by a locking pawl 26 which is pivotally con-

nected to the outer end of the frame and is provided with a notched inner end adapted to be brought into engagement with the notches in the adjusting bar whereby the latter will be securely held against longitudinal movement in either direction. 70

The cutting mechanism of the machine comprises a blade carrying arm 27 one end of which is pivotally mounted on a bearing stud 28 formed on the rear side of one end 75 of the frame as shown. The arm 27 has secured thereto a downwardly projecting cutting blade 29 which is adapted to be brought into engagement with the material to be cut when the arm 27 is swung downwardly. The blade carrying arm is operated by a raising and lowering lever 30. The lever 30 is fixedly mounted on one end 80 of a rock shaft 31 which is journaled in suitable bearings in the opposite side of 85 the frame over the stud 28 on which the arm 27 is mounted. The shaft 31 projects through a guide slot formed in the adjacent end of the blade carrying arm 27 whereby 90 said arm is guided in its movement and on the adjacent end of said shaft is secured a cam head 32 which is adapted to work in an oval shaped recess 33 formed in the adjacent end of the arm 27 whereby 95 when said shaft and cam head are turned in one direction by the lever 30, the arm 27 will be raised or lowered thereby bringing the edge of the blade into engagement with the strip of material for cutting off leads or 100 rules of the desired length. The arm 27 is limited in its downward movement by a stop lug 34 arranged on one side of the shaft bearing of the supporting frame as shown.

The table 3 of the machine is provided on 105 its lower edge with a supporting flange 35 while the spring table 4 is provided with work or material receiving lugs 36 having dovetail shaped lower edges which are adapted to slidably engage a dovetail shaped groove or channel 37 formed in the lower portion of the table 4 whereby said lugs 36 are held in adjustable engagement with the table and in line with the flange 35 on the table 34. By means of the lugs 36 110 the end of the strip of material will be held square while being cut. By hingedly connecting the cutting table 4 and yieldably supporting the inner end thereof, said end will move down under the pressure of the 115 blade when the strip is cut thereby holding the end of the strip and preventing the same from curling up while being cut.

From the foregoing description taken in 120 connection with the accompanying drawings, the construction and operation of the invention will be readily understood without requiring a more extended explanation.

Various changes in the form, proportion 125 and the minor details of construction may 130

be resorted to without departing from the principle or sacrificing any of the advantages of the invention as defined in the appended claims.

5 Having thus described our invention, what we claim is:

1. In a machine of the character described, a supporting frame, a stationary work supporting table arranged on one end 10 of said frame, a yieldably supported cutting table arranged in the other end of the frame, an adjustable stop block slidably mounted in said frame whereby the length of the material to be cut is gaged, a blade carrying 15 arm and means to operate said arm and blade for squaring the material.

2. In a lead and rule cutting machine, a supporting frame, a stationary table arranged in one end of said frame, a yieldably supported cutting frame arranged in the opposite end of the frame, a pica gage stop block slidably mounted in said frame, a point gage stop plate mounted in said block, means whereby said block is held in adjusted position in the frame and a cutting blade 25 operatively mounted on the frame whereby the material is cut into the desired length.

3. In a lead and rule cutting machine of the character described, a supporting frame, 30 a stationary table arranged in one end of said frame, a cutting table pivotally mounted at one end in the outer end of said frame, spring supports adapted to yieldably support the inner end of said table in position 35 to receive the material to be cut, a pica gage rack bar arranged in the frame, a stop block slidably engaged with said rack bar, a spring projected pawl carried by said block and adapted to operatively engage the 40 teeth on said rack bar whereby said block may be adjusted to half pica spaces, a supplemental gage bar mounted in said frame and adapted to be adjusted to increase the measuring capacity of the machine, said 45 gage bar having formed therein a series of stop notches spaced apart at pica lengths, a lever adapted to be engaged with said gage bar whereby the latter is held in its adjusted position, a lever operated cutting mechanism 50 whereby the material is severed to form leads or rules of the desired length.

4. In a rule and lead cutting machine, a supporting frame, a stationary table arranged in one end of said frame, a yieldably supported cutting table arranged in the 55 opposite end of said frame, a pica gage rack bar in said frame, said bar having formed therein half pica notches, a stop bar having a sliding engagement with said 60 rack bar, a spring pawl carried by said stop

block and adapted to engage said rack bar whereby the block is held in its adjusted position, a pawl releasing lever carried by said block, a point adjusting gage carried by said block, said gage comprising a revolvably 65 mounted plate having formed thereon a series of radially projecting lugs formed of different lengths, a set screw adapted to fasten said plate in position to project one of said lugs whereby a point adjustment is 70 provided for said stop block and a cutting mechanism arranged on said frame whereby the material may be cut to form leads or rules of the desired length.

5. In a rule and lead cutting machine, a supporting frame, a stationary supporting table arranged on one end of said frame, a pivotally mounted yieldably supported cutting table arranged in the opposite end of the frame, a stop block adjustably mounted 80 in the frame whereby the length of the material to be cut is gaged, a series of supporting lugs slidably mounted on said spring table whereby the material is held square while being cut and a cam operated cutting 85 mechanism adapted to sever the material into the desired lengths.

6. In a lead and rule cutting machine, a supporting frame, a stationary table arranged on one end of said frame, a yieldably supported table arranged on the opposite end of the frame, an adjustable stop block adapted to gage the length of the material to be cut, a blade carrying arm pivotally mounted on one side of said frame, a 90 blade carried by said frame and adapted to be brought into engagement with the material to be cut and to force said yieldably supported cutting table down whereby the material is held thereby preventing the latter 100 from curling while being cut, a rock shaft mounted in said frame, a cam fixedly mounted on one end of said shaft and adapted to engage said arm whereby the latter is raised and lowered to operate said blade and 105 an operating lever mounted on said shaft.

In testimony whereof we have hereunto set our hands in presence of two subscribing witnesses.
